MAGNETIC STRUCTURES FOR HIGH FREQUENCY ENERGY INTERCHANGE APPARATUS

Wilson Reese Turner, Mountain View, Calif., assignor to General Electric Company, a corporation of New York

Filed Nov. 22, 1957, Ser. No. 698,126

6 Claims. (Cl. 315—3.5)

This invention is directed to apparatus including magnetic structures and more particularly to such apparatus including magnetic structures for high frequency energy interchange devices wherein energy interchange is dependent upon interaction between an electron stream and radio frequency fields.

The electron tube known as a traveling wave tube is an example of such a device. In a conventional traveling wave tube, an elongated section of transmission line is mounted within an evacuated envelope. An input radio frequency wave is coupled onto the transmission line which is designed as a delay line or slow wave structure along which electromagnetic waves are propagated at some relatively small fraction of the velocity of light. In the most conventional form, the delay line is a conductive helix such as a helical metal coil. An electron stream is projected along a path near the helix in such a manner that the electrons in the stream and the radio frequency fields produced by the helix travel in close proximity. The velocity of the electron stream is made substantially equal to or synchronous with the axial component of the wave velocity along the helix. In operation, radio frequency waves traveling along the transmission line interact with the electrons in the stream to cause a redistribution of electrons in the form of partial bunching along the stream. As the wave and beam travel synchronously along the helix, the inverse phenomenon occurs and the bunched beam induces fields and currents along the helix. The amplitude of the wave increases along the helix because the electron stream gives up more energy to the helix than its abstracts from it. Consequently, an amplification of the radio frequency wave on the helix takes place. The region in which the electron stream and radio frequency fields interact is called the interaction region.

If the energy interchange described above is to take place, the electron stream must pass through the interaction region in close proximity to the radio frequency field produced by the transmission line. For most effective operation, electrons from the stream should be confined to the interaction region throughout its length. Since the space charge of the electrons in the stream tends to force them apart, some means must be provided to focus the stream throughout the interaction area to prevent the electrons from spreading and passing out of the interaction area. The usual method of focusing is to provide a unidirectional magnetic field having lines of force in the direction of the electron stream, by employing a solenoid which surrounds the entire traveling wave tube structure and produces an axial magnetic field. Another means of focusing the electron stream is to generate a periodic magnetic field along the axis of the traveling wave tube either by means of solenoids or by specially designed permanent magnets. In any case, if the magnetic lines of force produced along the axis of the tube are not straight (e.g., if they bow radially outwardly), they may be detrimental to the focusing of the electron stream. The problem of producing mag-

2

netic fields along the interaction region wherein the magnetic flux (lines of force) are perfectly straight is common to the energy interchange devices of the type under consideration here and is the problem to which the present invention is directed.

It is well known that parallel magnetic pole pieces having cross sectional dimensions which are of the order of, or smaller than, the distance between them produce a magnetic field between them which varies rapidly

- 10 with position along any straight line between them. This is true even along a straight line between the centers of the pole faces. This situation arises because of the fact that the magnetic lines of force bow out around the pole pieces. This effect is known as "fringing."
- 15 Due to the defocusing action of fringing flux lines, some means must be provided to straighten the flux lines in the interaction area if the magnetic field between such pole pieces is to be used for focusing an electron stream.

One solution to the problem is to use magnets with 20 pole pieces which are considerably larger in cross sectional dimensions than the pole separation in order to obtain the required field configuration necessary to focus an electron stream. This approach to the problem is objectionable since the diameter of the electron stream 25 to be focused is typically between 1% and 10% of the length of the electron stream (the length of the interaction region). Thus, using this solution to the problem, an extremely large volume of magnetic field is required to focus a stream with intrinsically small volume.

30 Accordingly, it is an object of this invention to provide a means of straightening flux lines or reducing fringing of the magnetic field between a pair of relatively widely spaced pole pieces of comparatively small transverse dimensions thereby to reduce the spreading tendency of the electrons in an electron stream directed axially along the magnetic field.

The use of a large solenoid for providing the magnetic field along the axis of a traveling wave tube is generally satisfactory. However, the solenoids required are 40 extremely large and heavy and require considerable power in order to provide the necessary axial magnetic field. The periodic focusing schemes either by solenoids or by specially designed permanent magnets may also be satisfactory for certain applications; however, they may 45 depend upon precise tube configuration, and may be too complicated, cumbersome, and unwieldy for general usage.

Accordingly, it is a further object of this invention to provide a means for decreasing variations in the magnetic focusing field along the axis of a high frequency energy interchange device when relatively widely spaced pole pieces of small transverse dimensions are used to produce the focusing magnetic field.

In carrying out the present invention, the magnetic lines of force between relatively widely spaced pole pieces of small transverse dimensions are straightened by placing discontinuous magnetically permeable members between pole pieces of the magnet. That is to say that the magnetic field between such pole pieces is made 55 nearly constant by utilizing specially shaped magnetically permeable members between pole faces.

The novel features which are believed to be characteristic of this invention are set forth with particularity in the appended claims. The invention itself both as to 60 its organization and method of operation together with further objects and advantages thereof may best be understood by reference to the following description taken in connection with the accompanying drawings in which:

Figure 1 is a perspective view of a magnet and magnetic field shaping means in accordance with an embodiment of this invention;

Figure 2 is a side elevation of a pair of magnetic poles

showing schematically the fringing magnetic flux lines between the poles in the absence of intervening magnetic materials;

Figure 3 is a side elevation similar to that of Figure 2 but of a slightly different scale, showing flux shaping members utilized in accordance with the teachings of the present invention and illustrating their action;

Figure 4 is another side elevation similar to those of Figures 2 and 3 having the center portion broken away and illustrating more widely separated magnetic poles 10 which require additional flux shaping members; and

Figure 5 is a central vertical longitudinal section through a traveling wave tube utilizing a magnet similar to the one illustrated in Figure 1 and the means of making the magnetic field strength constant along the axis of the traveling wave tube illustrated in the embodiment of Figure 1.

As illustrated in Figure 1, the field producing permanent magnet 10 has the configuration of a hollow ball flattened on opposite ends and having a pair of pie shape sections 8 and 9 removed from opposite sides of the magnet to allow the introduction of wave guide (not shown). Another way to describe the configuration of the permanent magnets illustrated is in terms of a surface of revolution as defined when a "C" lying on its side in such a manner that its open arms lie in a vertical position is rotated about a horizontal axis which extends through the outer extremities of the open arms of the "C."

The particular magnet 10 illustrated is one which was used in the application described herein and therefore is the one selected to illustrate the present invention. However, the invention is not limited to the use of such a structure. The pole pieces 11 and 12 for the magnet 10 are thick portions of magnetic material at the opposite flattened ends and on the axis of revolution of the "C" which defines the general shape of the magnet. It will be seen that one pole piece 12, the pole piece to the right in the illustration which is considered a south magnetic pole (see Diagram, Figure 2), has a centrally located aperture 13 therethrough for the insertion of the envelope of a traveling wave tube as is more fully described in connection with Figure 2.

As previously indicated, parallel magnetic pole pieces, such as pole pieces 11 and 12 of magnet 10, which have cross sectional dimensions of the order of, or smaller than the distance between them produce a magnetic field between them which bows outwardly. This is illustrated by magnetic lines of force or flux 14 and 14a in Figure 2 of the drawings. Flux lines at the outer edges of the poles 11 and 12 such as lines 14a are especially bowed. In order to straighten the lines of force 14 and thereby eliminate the defocusing action of the fringing magnetic field, and also to increase the useful magnetic flux between the pole faces 11 and 12, a pair of magnetically permeable flux shaping members 15 and 16 are provided (see Figure 3). Each of the magnetic flux shaping members 15 and 16 have the general shape of a frustum of a right circular cone and each is hollow with its inner surface substantially concentric with its outer surface. Further, both the inner and outer surfaces of the flux-shaping members 15 and 16 are continuous in the sense that they do not contain sharp bends or angles. In view of the conical shape of flux straightening members 15 and 16, they are referred to as "flux cones." The flux cones 15 and 16 are best seen in Figures 1, 3, 4, and 5.

In the arrangement illustrated in Figure 1, the flux cones 15 and 16 are held in position between the pole pieces 11 and 12 by means of a flux cone supporting cylinder 17 of non-magnetic material, such as brass, which is fitted between the pole pieces 11 and 12 of the magnet 10 in such a manner that its longitudinal axis coincides with a line between the centers of the pole faces 11 and 12 (the axis of the magnetic structure). The flux cone supporting cylinder 17 has its opposite ends

inserted in recesses 19 in the inside face of the pole pieces in order to hold it in position. A slightly enlarged portion is provided along the center portion of the flux cone supporting cylinder 17 so that the flux cones 15 and 16 may be slipped over the ends of the cylinder 17 and force fitted in position thereon. Thus, the cones are held in position with their axes coincident with the axis of the cylinder 17 and their apices directed toward the center of the structure (toward each other). In other words, the base of each of the flux cones 15 and 16 is nearest the adjacent pole face and the apex of each flux cone is directed away from the nearest pole face.

As illustrated, the angle (see angle θ of Figure 5) of the slant height (sides) of the flux cones 15 and 16 relative to their axis is approximately 45°. It has been found that angles between the cone sides and axes of between 30 and 60 mechanical degrees are satisfactory. However, for the particular application illustrated, it was found that the 45° angle was an optimum for providing a constant flux density or uniform magnetic field in the area of interest between pole pieces 11 and 12. In one model it was found that without the use of flux cones, the flux density between pole pieces 11 and 12 varied $\pm 25\%$ whereas the addition of the flux cones reduced the variation to $\pm 3\%$.

The flux straightening action of the cones 15 and 16 may best be described in connection with the somewhat schematic views of Figures 2 and 3. Figure 3 is a cross sectional view of the elements of the magnetic circuit 30 illustrated in Figure 1 with the associated magnetic lines of force 14. Figure 3 differs from Figure 2 only in the scale chosen and the addition of the flux cones 15 and 16 which change the contour of the magnetic lines of force 14. As illustrated the lines of force 14a near the outer edge of the pole pieces 11 and 12 which tend to bow out are intercepted by the flux cones 15 and 16 and guided into the center of the structure (the interaction region). Thus, the magnetically permeable flux cones 15 and 16 perform the dual function of concentrating and decreasing variations in the magnetic field between the pole pieces 11 and 12. The concentrating function increases the useful flux between the pole pieces and the variation decreasing function eliminates the electron stream defocusing action caused by fringing lines of flux.

The flux cones are effective to shape the flux lines 14 in this manner due to the fact that they are constructed of a material of high magnetic permeability, such as cold rolled steel. Since the high permeability material provides a path of low resistance for magnetic flux, such a material tends to collect magnetic flux lines in the area. Further, magnetic force lines both enter and leave a magnetic material at right angles to its surface. Thus, as illustrated in Figure 3, the fringing magnetic lines of force 14a between the pole pieces 11 and 12 are collected 50 by the flux cones 15 and 16 and enter the inside surface at right angles thereto, are guided along the cones toward their apices and leave the cones close to the axis of the structure. The walls of the flux cones 15 and 16 are preferably thick enough that they do not saturate appreciably and, as illustrated, they are of uniform thickness 55 so that the cones do not saturate unevenly. However, for particular magnetic circuit designs, it may be desirable to vary the wall thickness of the cones and such arrangements do not depart from the spirit and scope of the present invention.

For magnetic circuits where relatively small magnetic pole pieces are spread even farther apart than those illustrated in Figures 2 and 3, it may be desirable to use more than one pair of flux cones. This is true for two reasons. The first reason is that flux lines may again start to bow out between cones and it may be necessary to provide some means to prevent this fringing. The second reason for utilizing additional flux cones is to collect and direct additional flux lines into the interaction region 70 between the pole pieces 11 and 12.

Figure 4 illustrates an arrangement where two additional flux cones 20 and 21 are used in the magnetic circuit. The magnetic pole pieces and the pair of flux cones nearest these pole pieces are given the same reference numerals as the corresponding elements of Figure 3 since they are similar in configuration, placement and function. As illustrated in Figure 4, the two additional flux cones 20 and 21 also have the configuration of frusta of right circular cones. They are positioned between the first pair of flux cones 15 and 16 with their axes concentric and with their apices directed toward each other. The additional flux cones 20 and 21 have base circles which are considerably larger than the base circles of the first pair of flux cones 15 and 16 in order to collect fringing magnetic lines of force 14b not collected by the first pair of flux cones 15 and 16 and guide them in toward the central longitudinal axes of the structure. From an inspection of Figure 4, it may also be seen how the additional magnetically permeable flux cones 20 and 21 also collect and guide the fringing magnetic lines of force 14a back toward the longitudinal axis of the magnetic circuit.

Thus the flux cones 15, 16, 20 and 21 all decrease variations in the magnetic field between the pole faces 11 and 12. It is obvious that more such cones may be used where desired or necessary, the relative sizes of the cones may be varied, and the cones may be designed such that the wall thicknesses vary so that saturation is produced in some part of the flux cone. All of these variations may be made without departing from the spirit of the present invention. These variations are not all illustrated since the design variations are dependent upon the particular use. To obtain precise data for an individual application, resort should be had to a well known technique of using a flux plotting analog such as may be set up in an electrolytic tank. For such techniques see the book, "Electromagnetic Fields—Theory and Applications" by Weber, volume I—Mapping of Fields, pages 187-193, published by John Wiley and Sons, Inc., New York, New York, 1950 and the article entitled "Electrolytic Tank Design and Applications" by Phyllis A. Kennedy and Gordon Kent in Review of Scientific Instruments, volume 27, No. 11, pages 916-927, November 1956.

In Figure 5, the magnetic circuit 10 is utilized in conjunction with a conventional traveling wave tube 22. In this figure, only a portion of the magnet 10 is illustrated. As previously described, the flux cones 15 and 16 are held in position between the magnetic pole faces 11 and 12 by means of the non-magnetic cylindrical spacer 17.

The traveling wave tube 22 is provided with an envelope 23 that is generally long and cylindrical with an enlarged cylindrical portion 25 at one end which houses an electron stream producing gun 26 and a small slender cylindrical portion 27 which houses a long main interaction transmission line 28 which as illustrated is a helix. The small slender cylindrical portion 27 is positioned with its longitudinal axis in alignment with the longitudinal axis of the magnetic structure so that the magnetic field produced along this axis may be used to focus an electron stream directed along the longitudinal axis of the tube 22. In order to allow the tube 22 to be so positioned, apertures 13 and 24 (see Figure 5) are provided in pole pieces 11 and 12 respectively, the elongated portion 27 of tube 22 is then inserted through the apertures 13 and 24 in pole pieces 11 and 12 and the enlarged portion 25 of the tube 22 is positioned within a tube receiving recess or aperture 31 in the outer face of the magnetic pole piece 11 on the left hand side of the structure.

The electron gun 26 housed in the enlarged portion 25 at one end (the left as illustrated) of the evacuated envelope 23 forms and directs a stream of electrons along the axis of the envelope. The electrons which are formed into a stream are emitted from a cathode 33 in response to heat applied thereto by a heater 34. The heater 34 is illustrated as a high resistance coil member which must be connected to a source of voltage (not shown) in order

to produce heat necessary to make the cathode 33 emit. The electron stream 32 is formed and projected along the axis of the tube by a pair of centrally apertured electron stream focusing and accelerating electrodes 35 and 36 which are located in the enlarged portion 25 of the tube 22 between the electron emitting cathode member 33 and the beam helix or main transmission line 28. Since the beam helix 28 is positioned inside the slender portion 27 of the envelope 23 with its axis coincident with the tube axis, the electron stream flows down the length of the tube in close proximity thereto, thus providing an interaction region along the tube axis. A collector anode 37 is positioned at the opposite or output end of the structure to dissipate residual energy in the stream.

Electromagnetic waves are introduced onto the beam helix 28 by means of a conventional wave guide 40 which is brought in through one of the removed "pie shaped" sections 8 and 9 (best seen in Figure 1) of magnet structure 10 and through an aperture 41 in the end of flux cone supporting cylinder 17 near the electron gun end of the tube 22. In order to transfer the electromagnetic wave to the beam helix, the elongated portion 27 of tube 22 is positioned within an aperture 39 through input waveguide 40. The amplified electromagnetic wave is extracted from the beam helix 28 at the opposite end of the tube by another waveguide 42 which is also brought in through the magnet structure 10 as described with respect to the input waveguide 40. Another aperture 43 is provided in the opposite end of the flux cone supporting cylinder 17 to allow the output waveguide 42 to be introduced. The slender elongated portion 27 of tube 22 passes through an aperture 44 in the output waveguide 42.

The electromagnetic wave introduced by means of input waveguide 40 is propagated down the beam helix 28 in close proximity to the electron stream 32 produced by the electron gun 26. The electromagnetic wave so propagated is amplified through the mechanism of interaction with the electron stream 32 and the amplified electromagnetic wave is extracted through output wave guide 42.

The permanent magnetic focusing member 10 produces a magnetic field axially along the tube 22 which is sufficiently strong to prevent the space charge of the electrons in the stream from spreading them to such an extent that they pass out of the interaction region and/or intercept the helix. Since the magnetically permeable flux cones 15 and 16 decrease variations of the magnetic field between the pole pieces 11 and 12 and since the axis of the tube 22 coincides with a line between centers of the pole pieces 11 and 12, the flux cones 15 and 16 serve to make the magnetic field constant along the axis of the traveling wave tube 22. In this manner, the problems attendant on providing specially shaped magnets or on designing periodic focusing arrangements into the traveling wave tube is circumvented since the magnetic path external to the poles 11 and 12 may take any convenient shape. Also the magnet weight may be reduced as compared to the case in which pole pieces of larger cross sectional dimensions in the gap are used since a smaller volume must be driven by the field producing magnet 10.

While a particular embodiment of the invention has been shown and described, it will of course be understood that the invention is not limited thereto since many modifications both in the magnetic circuit arrangement and in the instrumentalities employed may be made. It is contemplated that the appended claims will cover any such modifications as fall within the true spirit and scope of this invention.

What I claim is new and desire to secure by Letters Patent of the United States is:

1. A high frequency energy interchange device including an elongated evacuated envelope, electron gun means at one end of said envelope for projecting a stream of electrons along the length of said envelope, collector means at the opposite end of said envelope to dissipate residual energy in said electron stream, an elongated section of

transmission line mounted within the envelope between said electron gun means and said collector means in coupled relationship with the electron stream, and magnetic circuit means positioned coaxially with respect to said evacuated envelope to produce a magnetic field along the length of said envelope to provide focusing action for said electron stream, said magnetic circuit means comprising a pair of magnetic pole pieces and at least a pair of flux straightening members of a material having a high magnetic permeability, said flux-straightening members having the configuration of hollow cone frusta with continuous inner and outer surfaces without angles therein and being positioned coaxially between the pole pieces with the apices of the cones directed toward each other.

2. A high frequency energy interchange device including an elongated evacuated envelope, electron gun means at one end of said envelope for projecting a stream of electrons along the length of said envelope, collector means at the opposite end of said envelope to dissipate residual energy in said electron stream, an elongated section of transmission line mounted within the envelope between said electron gun means and said collector means in coupled relationship with the electron stream and magnetic circuit means positioned coaxially with respect to said evacuated envelope to produce a magnetic field along the length of said envelope to provide focusing action for said electron stream, said magnetic circuit means comprising a pair of relatively widely spaced magnetic pole pieces having cross sectional dimensions which are of the order of, or smaller than the distance between them including a plurality of pairs of coaxial flux straightening hollow cone frusta of a material having a high magnetic permeability between the pole pieces, each one of each pair of hollow cone frusta having continuous inner and outer surfaces without angles therein and being equidistant from an opposite pole piece with the apex of the cone directed toward the other one of said pair, and each pair of flux cones being positioned a different distance from said pole pieces.

3. Apparatus as set forth in claim 2 wherein the pairs of flux straightening cone frusta which are displaced by progressively greater distances from the pole pieces have progressively larger bases.

10

15

4. Apparatus for decreasing variations of the magnetic field between a pair of magnetic pole pieces including at least a pair of flux straightening members of a material having a high magnetic permeability and having the configuration of hollow cone frusta, said pair of magnetically permeable members having continuous inner and outer surfaces without angles therein positioned coaxially between the pole pieces with the apices of the defining cones directed toward each other.

5. Apparatus for decreasing variations of the magnetic field between a pair of relatively widely spaced magnetic pole pieces having cross sectional dimensions which are of the order of, or smaller than the distance between them including a plurality of pairs of hollow coaxial flux

15

straightening cone frusta of a high magnetic permeability material between the pole pieces, said hollow cone frusta having continuous inner and outer surfaces without angles therein, each one of each pair of cone frusta being equidistant from an opposite pole piece with the apex of the cone directed toward the other one of said pair, and each pair of flux cones being positioned a different distance from said pole pieces.

6. Flux straightening apparatus as defined in claim 5 wherein the pairs of flux straightening cone frusta which are displaced by progressively greater distances from the pole pieces have progressively larger bases.
